US00D871249S

(12) **United States Design Patent** (10) Patent No.: **US D871,249 S**
(45) Date of Patent: **** Dec. 31, 2019**

(54) **WATCH BUCKLE**

(71) Applicant: **SHENZHEN BAILINNIAO TECHNOLOGY CO., LTD.**, Shenzhen (CN)

(72) Inventor: **Jianjie Deng**, Guilin (CN)

(73) Assignee: **SHENZHEN BAILINNIAO TECHNOLOGY CO., LTD.**, Shenzhen (CN)

(**) Term: **15 Years**

(21) Appl. No.: **29/702,291**

(22) Filed: **Aug. 19, 2019**

(51) LOC (12) Cl. **11-01**

(52) U.S. Cl.

USPC **D11/94**

(58) **Field of Classification Search**
